UNITED STATES PATENT OFFICE.

WILLIAM C. TULL AND ROY J. BRISTOL, OF STANTON, NEBRASKA, ASSIGNEES TO VERA BIEDINGER, JOSEPH LAMPE, GORDON B. BUTTERFIELD, AND GEORGE H. TATGE, ALL OF NORFOLK, NEBRASKA.

WRENCH.

Application filed February 15, 1924. Serial No. 693,063.

To all whom it may concern:

Be it known that we, WILLIAM C. TULL and ROY J. BRISTOL, citizens of the United States, residing at Stanton, in the county 5 of Stanton and State of Nebraska, have invented new and useful Improvements in a Wrench, of which the following is a specification.

The object of our said invention is the 10 provision of a wrench of pliers type embodying such construction that the wrench is susceptible of ready adjustment and is highly efficient and reliable in use and at the same time convenient to handle.

15 To the attainment of the foregoing, the invention consists in the improvement as hereinafter described and definitely claimed.

In the accompanying drawings, forming 20 part of this specification:—

25 Figure 1 is a side elevation of our preferred form of wrench.

Figure 2 is an edge elevation of the wrench.

25 Figure 3 is an enlarged detail view illustrative of the connection between the handles.

Similar numerals of reference designate corresponding parts in all of the views of the drawings.

30 Among other elements our novel wrench comprises a handle 1 with an integral toothed jaw 2 at its forward end and an enlargement 3 at the inner side of its rear or heel end. It will also be noted that the said handle 1 is provided at a point adjacent to the jaw 2 with a slot 4.

The wrench also comprises a movable jaw 5, a handle 6, a nut 7 and link rods 8, said link rods 8 being threaded into said nut. 40 The handle 6 is provided with a lateral intermediate projection 9 to bring up against the inner edge of the handle 1.

45 As illustrated the jaw 5 is toothed at 10, is pivotally connected at 11 to the handle 6 and is provided with a hook-like arm 12, the said arm 12 being disposed and movable in the slot 4 so as to retain the jaw 5 in proper association with the jaw 2 while permitting adjustment of the jaw 5 with 50 respect to the jaw 2.

As illustrated one link rod 8 is pivotally connected to the projection 3 of handle 1, and the other link rod 8 is similarly connected to the projection 9 of the handle 6;

also, the said link rods 8 are reversely 55 threaded to engage the corresponding threads in the end portions of the nut 7 which latter is intended to be turned about its axis and is therefore exteriorly of angular form in cross-section. 60

Manifestly by adjusting the nut 7 on the link rods 8 the engaging face of the jaw 5 can be readily moved away from and toward the engaging face of the jaw 2, and it will also be noted that the adjustable positioning of the nut 7 on the link rods 8 will adjustably fix the two jaws with respect to each other so as to adapt the wrench to take safe hold of an article that is in position between the engaging faces 70 of the jaws.

As illustrated the projection 9 meets with handle 1 immediately after handle 6, in closing, has passed the highest point of tension, preventing jaws 2 and 5 from loosening their grip, thereby causing them to firmly lock on an article that is in position between the engaging faces of the jaws. 75

Notwithstanding the practical advantages of our novel wrench as pointed out in the foregoing it will be manifest that the wrench is simple and inexpensive in construction and is well adapted to withstand the rough usage to which wrenches are ordinarily subjected. 80

We have entered into a detailed description of the construction and relative arrangement of parts embraced in the present and preferred embodiment of our invention in order to impart a full, clear and exact 85 understanding of the said embodiment. We do not desire, however, to be understood as confining ourselves to the specific construction and relative arrangement of parts inasmuch as in the future practice of the invention various changes and modifications may be made such as fall within the scope 90 of our invention as defined in our appended claim. 95

Having described our invention, what we 100 claim and desire to secure by Letters-Patent, is:—

A wrench comprising a handle having an integral jaw at its forward end and an enlargement on its inner side at its rear end 105 and also having a slot slightly in rear of said jaw, a second jaw having a hook-like arm disposed and movable in the said slot,

a handle pivotally connected to the second-named jaw and extending rearwardly therefrom in spaced relation to the first-named handle and having an intermediate 5 enlargement at its inner side, a link rod pivotally connected to the rear enlargement on the first-named handle, a link rod pivotally connected to the enlargement on the other handle; said link rods reversely threaded, and a nut having reversely threaded sockets receiving and engaging said rods.

In testimony whereof we affix our signatures.

WILLIAM C. TULL.
ROY J. BRISTOL.
